LE ROY WERTS, OF MILFORD, MISSOURI.

FUEL-VAPORIZER.

1,317,248.

Specification of Letters Patent. Patented Sept. 30, 1919.

Application filed October 27, 1917. Serial No. 199,209.

To all whom it may concern:

Be it known that I, LE ROY WERTS, a citizen of the United States, and a resident of Milford, in the county of Barton and State 5 of Missouri, have invented certain new and useful Improvements in Fuel-Vaporizers, of which the following is a specification.

The invention relates to carbureters or vaporizing apparatus and chiefly to such apparatus for use with kerosene or the like as fuel for the operation of motor car engines. One object of the invention is to produce a 10 simple, strong, durable, efficient and economical fuel vaporizer.

15 A further object is to utilize the heat of exhaust gases from the engine for coöperating in the vaporization of the fuel.

Another object is to provide means whereby either light or heavy liquid fuel may 20 be supplied for vaporizing purposes, and whereby a charge of either of such fuels in the vaporization chamber may be evacuated in the event it is desired to change from one fuel to the other.

25 With these general objects in view, the invention consists in certain novel and peculiar features of construction and combinations of parts, as hereinafter described and claimed; and in order that the invention 30 may be fully understood reference is to be had to the accompanying drawings, in which:—

Figure 1, is a diagrammatic view of apparatus embodying the invention.

35 Fig. 2, is a side view of the apparatus, with the dash of a motor car, shown in vertical section.

Fig. 3, is a view partly in elevation and partly in section of the vaporizer element of 40 the apparatus.

Fig. 4, is a diagrammatic view of a resistance coil forming part of the vaporizer element.

Fig. 5, is an enlarged central section of a 45 valve whereby the character of the fuel employed in the vaporizer is controlled.

In the said drawing, 1 and 2, indicate supply pipes leading respectively from suitable tanks, (not shown) for holding two kinds 50 of liquid fuel, such as gasolene and kerosene, to chambers 3 and 4, controlled by valves, (not shown) and communicating respectively with chambers 5 and 6, which chambers are of that type having floats, 55 (not shown) for operating the valves of chambers 3 and 4, so as to automatically

regulate the volume of liquid fuel supplied by pipes 1 and 2. As the float chambers may be of conventional type the construction thereof is not detailed.

60 Adjacent the float chambers, is a valve for selectively controlling the character of fuel to be used, said valve being constructed as follows: 7 is a tapering shell containing a rotary plug valve 8, provided with an intake port 9, for communicating with either of a pair of ports 10 and 11, of the shell, which ports are respectively connected by pipes 12 and 13, with the float chambers 5 and 6, so that gasolene or kerosene may enter the hollow or chamber of the plug valve according to the adjustment thereof. The plug is also provided with drain ports 13^a and 14, at the lower end, the ports 13^a and 14 being adapted respectively for simultaneous communication with the shell or casing port 19 and with a drain port 15, in the shell, and from said last-named port, a drain pipe 16, leads to a convenient point of discharge. The valve is furthermore provided with diametrically opposite ports 17 and 18, in a plane between the intake and drain ports, said ports 17 and 18 communicating respectively with the shell port 19, when plug port 9 communicates respectively with shell ports 80 10 or 11.

85 A pipe 20, leads from shell port 19 to the lower end of a vaporizer, which is so related to the float chambers that it cannot overflow, and to the drain port 15, so that it can 90 be drained thereby. To turn the plug so that it shall receive from either of said float chambers and supply the vaporizer, or effect the drainage of the latter, a stem 21 extends from the plug through the dash 22, of the 95 car and is provided with a handle 23, which the driver adjusts with respect to a marked disk 24, containing opposite marks G and K, for gasolene and kerosene respectively, a mark D, for drainage, and a mark N for 100 neutral. The adjustment of the handle to a point corresponding to a particular mark indicates the position of the plug valve.

105 The vaporizer 25, is preferably provided with a heavy core which may consist of a valve-controlled branch pipe 26 of the exhaust manifold of the engine, so that the heat therefrom can be utilized in raising the temperature of the liquid fuel entering the vaporizer from pipe 20. The outer wall 27 110 of the vaporizer is preferably of thin metal, and its chamber is partitioned from one end

thereof to the other by a spiral partition 28, so that liquid fuel entering the vaporizer at one end from pipe 20, shall travel in a thin stream to the opposite end of and escape 5 from the vaporizer in the form of a vapor, through the pipe 29.

The vapor discharge pipe 29 communicates with the intake manifold 30 of the engine, and is provided within said intake 10 manifold with a jet nozzle 31, for discharging vapor into said manifold, and to regulate the volume of vapor or liquid fuel passing to said nozzle, pipe 29 is provided with a needle-valve 32. The intake manifold is 15 provided with the usual auxiliary air intake passage 33, controlled by the customary check valve 34, not detailed.

A casing 35, of insulating material, is provided with a series of contacts 36, extending 20 into a longitudinal groove 37, and electrically connected to or engaged therein with a series of contacts 38, of a resistance or heating coil 39, fitting snugly around the vaporizer so that heat generated in the coil shall 25 effect vaporization of liquid fuel in the vaporizer, the inner wall 40, of the coil being preferably of thin metal to facilitate the heating of the vaporizer.

A bracket 41, is secured to the casing 35, 30 and forms a journal bearing for one end of a shaft 42, operable from the driver's seat, and mounted on said shaft is a contact arm 43, for successive engagement with said contacts 36. A wire 44, extends from the bracket 41, 35 to a two-way switch 45, adapted to close against either of a pair of contact posts 46 or 47, and the latter is connected by a wire 48, to a storage battery 49. The battery is connected by a wire 50, to one end of the heating 40 coil, and by a wire 51, to a generator 52. The generator is connected by a wire 53, to contact post 46.

It will be apparent that when contact arm 45 is in the position shown by Fig. 4, and the switch is engaging the contact post 47, the current will flow from the battery without passing through the heating coil and hence generate no heat, and that by shifting the said arm onto the successively presented 50 contacts 36, increasing lengths of the coil are brought into the circuit for the purpose of generating the desired volume of heat for vaporization of the liquid in the vaporizer. When the arm is positioned so that the current 55 shall flow through the entire length of the coil, it is intended that sufficient heat shall be generated to almost instantly vaporize the liquid fuel passing through the vaporizer so that the vapor when mixed with air, shall be susceptible of instant explosion and therefore suitable for starting the engine even though the same is cold.

After the engine has been started, the vaporizer can be cut out of circuit with the 60 storage battery and into circuit with the 65

generator, by moving the switch lever from contact post 47 to contact post 46. The arm 43 can then be adjusted to cut out part of the coil and thereby diminish the amount of current consumption to that volume which 70 experience directs as necessary for effecting proper operation of the engine. After the engine has been in operation long enough to get thoroughly warmed up, it will only be necessary to keep the kerosene heated to the 75 flashing point, which is ordinarily about 150 degrees Fah. If conditions warrant, the circulation of current from the storage battery or generator, may be arrested by opening the 80 switch.

The apparatus as shown can be used on cars lacking a starting system or equipped with such system. On cars lacking such system the entire apparatus will be used so that they can be started on gasoline and then 85 switched to kerosene. Cars having an electric starter can start and run on kerosene.

From the above description, it will be apparent that I have produced a kerosene vaporizing apparatus which can be operated 90 efficiently and economically, and by which an engine can be started as well as maintained in operation, and while I have illustrated the preferred embodiment of the invention, it is to be understood that it is susceptible of modification in various particulars without departing from the scope of the 95 appended claims.

I claim:

1. The combination of a liquid fuel vaporizer, means to heat the same, a pair of chambers for different liquid fuels, a hollow valve having a port to receive from either of said chambers and a pair of discharge ports for respective discharge accordingly as the first-named port receives from one of said chambers or the other.

2. The combination of a liquid fuel vaporizer, means to heat the same, a pair of chambers for different liquid fuels, and manually operable means for effecting the transmission of fuel from either of said chambers to the vaporizer, for shutting off the supply of fuel from both simultaneously, and for draining the vaporizer of its contents while the said supply chambers are both cut off.

3. The combination of a liquid fuel vaporizer, means to heat the same, a pair of chambers for different liquid fuels, a hollow valve having a port to receive from either of said chambers and a pair of discharge ports for respective discharge accordingly as the first-named port receives from one of said chambers or the other; said valve also having a fourth port between said pair of ports and 120 a drain port for operation when the fourth port is open.

4. The combination of a liquid fuel vaporizer, means for heating the same, a pair of chambers for different liquid fuels, a valve 130

casing having a pair of ports respectively connected to said chambers, a single discharge port connected to said vaporizer, and a drain port; and a valve in said casing having a receiving port for registration with either of said pair of ports, a pair of discharge ports for respective registration with said single discharge port of the casing accordingly as the first-named valve port registers with one of said pair of casing ports or the other, and a pair of drain ports, one for communication with the drain port of said casing and the other adapted to register with the discharge port of the valve casing when the receiving port of the valve is not in communication with either of the said pair of casing ports.

5. The combination of a liquid fuel vaporizer, means to heat the same, a pair of chambers for different liquid fuels, a hollow 20 valve having a port to receive from either of said chambers and a pair of discharge ports for respective discharge according as the first-named port receives from one of said chambers or the other; said valve also 25 having a fourth port between said pair of ports and a drain port for operation when the fourth port is open, and means for indicating the adjustment of the valve.

In witness whereof, I hereunto affix my 30 signature, at Towanda, in the county of Butler and State of Kansas, this 18th day of Oct., 1917.

LE ROY WERTS.
